LOAD DISCHARGING CAR

Argyle Campbell, Chicago, Ill., assignor to Enterprise Railway Equipment Company, Chicago, Ill., a corporation of Illinois

Application July 24, 1937, Serial No. 155,460

9 Claims. (Cl. 105—251)

My invention relates to improvements in load discharging cars, and is especially related to that type of car used in ballasting work on railroads, wherein the load is gradually discharged in a uniform flow under the control of the operator, and wherein the lading may be deposited either to the sides of the track or between the rails or simultaneously to the center and one side or simultaneously to the center and both sides.

10 An object of my invention is to provide a car having large discharge openings unobstructed by cross bracing members such as would normally interfere with the free flow of the lading.

Another object of my invention is to provide 15 a car of the character described, having hopper walls formed at their lower margin of such shape that they function as girders by which to obtain the necessary strength to span large door openings without buckling of the hopper walls.

20 Still another object of my invention is to provide an improved car of the character described, having fixed upper hopper sections on each side of a longitudinally extending center member, and to provide means whereby lading will be directed from said fixed hoppers through discharge outlets to distributing sub-hoppers of greater length than the discharge outlets. By providing chute-like 25 distributing sub-hoppers of greater length than the discharge outlets I mitigate the confining 30 tendency of the discharging lading as it flows through the chutes and thus ensure a smooth and steady flow of the discharging material.

My invention also provides for the standardization of parts entering into the construction of 35 cars of the character described, making for simplicity, lightness in weight, and moreover permitting a uniform speed of door operation when the doors are being opened for center or side discharge. My improved design provides for 40 center and side discharging doors of substantially uniform construction and of equal size and so arranged as to have their respective swinging edges disposed on a common horizontal plane when the doors are in closed position.

45 My improvements further include improved door operating mechanisms for controlling the movement of the doors.

My invention further resides in certain details 50 of construction and improvements of parts, such as will be more fully pointed out hereafter and claimed.

For further comprehension of my invention, reference may be had to the accompanying drawings wherein:

55 Fig. 1 is a sectional plan view of the major

portion of a hopper car embodying my improvements, said view being taken above the hopper structures;

Fig. 2 is a vertical longitudinal elevational view of the car illustrated in Fig. 1, the left-hand half 5 of the figure representing a sectional view taken on a line 2—2 of Fig. 1, and the right-hand half of the figure being a full side elevational view of the car;

Fig. 3 is a transverse vertical sectional view on 10 an enlarged scale, taken through the lower portion of the hopper car substantially on a line 3—3 of Fig. 1;

Fig. 4 is a fractional plan view on an enlarged 15 scale, of a portion of the car, showing as much of the car as necessary to illustrate one of the hopper sections and the associated car structure;

Fig. 5 is a vertical elevational side view of the 20 structure illustrated in Fig. 4;

Fig. 6 is a fractional sectional plan view taken 25 through one of the hoppers on a line 6—6 of Fig. 3;

Fig. 7 is a vertical, longitudinal sectional view 30 of that portion of the car illustrated in Fig. 6 and as viewed on a line corresponding substantially to a line 7—7 of Fig. 6; and

Fig. 8 is a fractional vertical sectional view 35 on an enlarged scale as taken through one of the hopper end walls on the line 8—8 of Fig. 6.

In said drawings, the center sill of the car is 40 shown as consisting of two beam members 101—101, each having a vertical web 102, top flange 103, and outstanding bottom flange 104. The top flanges 103 of the respective beams face 45 towards each other and are welded as at 105. Surmounting the center sill for a portion of its length are inverted V-shaped caps 106 welded to the center sill proper at 107, said caps being employed only where the center sill is exposed to 50 the lading for the purpose of preventing lodgment of lading on the top of the center sill.

The car sides, which are indicated at 108, are 55 of the conventional type including a vertical plate 109 and top and bottom reinforcements 110 and 111 respectively. The cross members of the car include a central crossbeam 113 and the body bolsters 114, said respective members forming supports for sloping floor sheets 115 and 116 respectively. The floor sheets 115 and 116 respectively cooperate with side sloping sheets 117 and with portions of the center sill to form fixed 60 hopper sections on each side of the center sill.

The sloping floor sheets 115, 116 and 117, adjacent their lower margin, are formed with ver- 65

tical wall sections or portions 118, 119 and 120 respectively, which commence at an appreciable distance above the lower face of the center sill and terminate substantially in alignment with the lower face of the center sill. The vertical wall portions 118, 119 and 120, in cooperation with the outer portion of the center sill lower flange 104, define a rectangular discharge outlet at a level corresponding substantially with the level of the center sill lower margin. The said vertical wall portions 118, 119 and 120 are reinforced outwardly of the discharge outlet by means of angle members 121 for sections 118 and 119, and angle members 122 for sections 120. Each of the said angle members 121 and 122 is disposed with one of its flanges thereof extending horizontally in substantial alignment with the lower flange 104 of the center sill, thereby providing a ledge 123 extending around the discharge outlet.

Below the level of the discharge outlet there is provided for each hopper a distributing sub-hopper composed in effect of a pair of transversely extending beams 124—124 and doors 125 disposed between said beams. The beams of the pair included in each sub-hopper are spaced from each other lengthwise of the car, and interposed between said spaced beams are the doors 125 arranged in the form of a V pivoted adjacent its apex on a pivot 126. The beams 124, which are preferably of channel formation including a web 127 and top and bottom flanges 128 and 129 respectively, are disposed in underlying relation with respect to the center sill and with respect to the ledge 123 of the hopper. The said beams 124 are located an appreciable distance beyond the ends of the discharge outlet and the doors 125 are correspondingly extended thereby providing sub-hoppers which are longer than the discharge outlet above said sub-hoppers. The pivot 126 consists of a rod extending through the beams 124, and the ends thereof are mounted in brackets 130 disposed on the outer sides of the channel members.

The channel members 124 are extended transversely of the car beyond the discharge outlets and beyond the swinging edges of the doors thereby providing chute-like structures which operate to confine the flow of the lading within predetermined limits and enable the utilization of the cars in road-bed ballasting service. Angle-shaped brackets 131 are secured to the extended portions of the beams 124. Each bracket has a wall section 132 extending lengthwise of the car and another wall section 133 extending transversely of the car. The section 133 is secured to the beam 124 by means of rivets 134, the top flange 128 of the channel being cut away as at 135 to accommodate said section 133. The said section 133 is flanged at the top at 136 to conform to the slope of the hopper floor and is secured thereto by means of rivets 137. The section 132 is united with the car side walls through the medium of an angle member 138. The beams 124 are further braced relatively to the center sill by means of angle braces 139.

The ledge 123 is preferably formed to present, in combination with the flange 104 of the center sill, a continuous flange around the discharge outlet by extending the longitudinal angle 122 to position it between the respective wall sections 132 and welding the ends of said angle 122 to the ends of the transversely extending angles 121. Adjacent the center sill the angle members 121 are coped out to permit of the extension of the

vertical flange of said angle above the center flange 104, and a welded connection may be made with the center sill flange 104 as at 140.

The respective doors 125 of the pair are made of similar construction, each consisting of a body portion made of a plate 141 bent adjacent the swinging edge of the door to provide a ledge portion 142 to underlie the ledge 123 when the door is in closed position. The doors are braced lengthwise of the car by beams 143 and 144 disposed adjacent the swinging and hinged ends of the doors respectively, said beams being preferably of Z-shape. The doors extend to within a comparatively short distance of the beams 124, and the gaps between the beams and doors are sealed by welded strips 145. The hinge edges of the doors are scrolled at 146 to encircle the pivot 126, the scrolled hinge on one door intercalating with the scrolled hinge on the opposite door in such a manner that when the doors are in assembled relation the hinges of the respective doors form a substantially continuous hinge.

The scrolled part 146 of the door is composed of a plate bent to form a loop with the ends of the plate brought into overlapping relation and with one end extending beyond the other and lapping one of the flanges 147 of the beam 143. The loops are formed considerably larger than the supporting pivot 126 for the purpose of preventing any possibility of the parts binding in the event of water percolating within the hinges and freezing, and also to allow for any irregularities in manufacture.

The doors are strengthened at right angles to the pivotal axis of the doors by a series of reinforcements 148, 149 and 150, the latter being of angle shape and disposed with one of their flanges at right angles to the door plate. The door on one side of the sub-hopper in open position forms a continuous slope with the companion door when the latter is in closed position; the slope of the doors from the horizontal plane in either the fully closed or fully opened position is preferably at an angle of approximately 36 degrees. With both doors of a sub-hopper in the fully open position, there is presented an inverted V-shape shedding member disposed midway of the hopper discharge outlet.

The doors are operated by means of longitudinally extending operating shafts located outwardly beyond the free edges of the doors. The center doors of each subhopper are operated in unison by an operating shaft 151 disposed within the center sill, and each side door of each hopper is independently operated by an operating shaft 152. Connections between each operating shaft and its associated door are effected through the medium of chains or other suitable flexible connections 153, the connections extending through openings 154 in the door plates and secured to the vertical flange of member 150 by means of an adjusting eyebolt 155 as best indicated conventionally in Fig. 5. The chains for the respective doors are located intermediate the vertical wall sections of the sloping end floors and the adjacent beams 124, said chains in their progress from the shaft to the door being deflected from a straight line path by being passed over deflecting shoes 156 for the center doors and 157 for the side doors. The said deflectors are formed with a base portion 158 which rests upon the ledge 123 and is secured thereto by rivet 159. Above the base portion 158 there is provided an arcuate-shaped bearing or shoe 160 over which the chain is adapted to slide. The

chain is guided through a socket portion 161 which is preferably extended downwardly to meet the door and which acts as a shield to protect said chain from contact with the lading when the door is in closed position and also seals the opening in the door through which the chain passes.

The deflectors are provided with side wall guiding flanges 162, one of said flanges being also secured to the vertical flange of the angle 121 and with the related vertical wall portion. In the case of the deflectors 157 for the side doors, the guiding flange is extended upwardly and is attached directly to the vertical wall portion as indicated at 163.

The chains connect directly with winding sheaves or drums 164 for the center doors and at 165 for the side doors. Said sheaves 164 for the center doors are extended lengthwise of the shaft a sufficient distance to accommodate oppositely winding chains for the respective doors, said chains extending through openings 166 formed in the center sill webs.

Rotation of the shafts is preferably carried out by means of worm and gear mechanisms indicated conventionally at 167 and housed in housings 168 for the center doors and 169 for the side doors. Each said worm and gear housing also forms the support for one end of the shaft operated thereby, the opposite end of the respective shafts being carried in bearings 170 for the center doors and 171 for the side doors.

The worm and gear housing 168 is secured to the center sill webs as indicated at 172 and riveted to the vertical web 127 of the beam 124 at 173, the top flange of the beam being cut away at 174 in order to accommodate the housing. Rotation of the center operating shaft 151 is effected through the medium of a cross shaft 175 which is extended to the respective sides of the car and through bearings 176 carried by the wall 132. Outwardly of said wall there is disposed on each end of the shaft a locking ratchet wheel 177 with which a locking pawl 178 cooperates. The locking pawls 178 at the corresponding ends of the shaft are operable in unison by means of an additional shaft 179 to which the respective pawls 178 are attached through the medium of a bell-crank operating handle 180. The mechanism enables the complete operation of locking or releasing the center doors to be effected from either side of the car.

The operation of the side doors is carried out through the medium of short transverse shafts 181, each having a locking ratchet wheel 182 thereon and a locking pawl 183 cooperable with said ratchet wheel. Each operating shaft is provided outwardly of the locking ratchet with an operating ratchet wheel 184 with which a suitable operating handle (not shown) is adapted to engage for effecting a step-by-step rotation of the shaft.

The arrangement of the hopper construction, by reason of the channel-shaped lower margins provided by the sloping floor sections and lower vertical wall sections in combination with the ledge portions, provides the necessary strength both vertically and laterally to resist buckling of the hopper walls and thus enables the use of very large door spans.

The ends of the hoppers are further strengthened, as best seen by reference to Fig. 8, by welding the angle members 121 to the top of the channel members 124, as indicated at 185, thereby providing a continuous wall effect between the 75 hopper end floors and the lower channels. The

continuous structure provided by welding the angle 121 to the channel member 124 results in the said hopper end wall channel-shaped reinforcement functioning as a box-like reinforcement disposed above the door and presenting a 5 convenient housing for the door chains.

The fact that the sub-hoppers are of longer length than the discharge outlets of the upper hoppers permits a slight spreading out of the material as it flows between the confining walls 10 of the baffle members after leaving the discharge outlets. This capacity for expansion of the material in the sub-hoppers counteracts the tendency of the lading to arch in the door openings and assures a smooth flow of lading, such as becomes of importance when discharging material from a moving car in the course of ballasting operations.

I claim:

1. In a car of the character described, the combination with a longitudinally extending member dividing the car lengthwise into two hopper sections; partitions extending transversely of the car and adapted to define with said longitudinally extending members a plurality of fixed 25 hoppers terminating in discharge outlets; and a sub-hopper disposed below each said outlet and extended lengthwise of the car beyond the discharge outlet to present a load-receiving receptacle of greater length than the discharge 30 outlet of said associated fixed hopper, each said sub-hopper being provided with vertically extending end walls and doors lying between said end walls for directing lading to either side of the discharge outlet or to both sides thereof 35 simultaneously.

2. In a car of the character described, having a longitudinally extending center member formed with an outstanding lower horizontal flange on each side thereof; a four-sided load-containing 40 hopper on each side of the center member, each hopper being defined in part by a portion of the center member and on the other three sides by sloping walls, said sloping walls at their lower portions having a substantially horizontally extending flange disposed in alignment with the lower flange of the center member and constituting therewith a four-sided marginal reinforcement around the hopper; and a sub-hopper disposed below the said upper hopper and including 45 50 V-arranged doors adapted to abut two sides of said four-sided marginal reinforcement when in closed position.

3. In a railway car of the character described, the combination with a longitudinally extending 55 center member including a laterally extending lower marginal flange on each side thereof; a four-sided load-containing hopper section on each side of the center member, each section being defined in part by a portion of the center 60 member on one side of the hopper and on the other three sides by sloping walls, said sloping walls at their lower portions terminating in a vertical wall section and a substantially horizontally extending margin, said margins of the 65 three walls, in combination with the lower flange of the center member, forming a four-sided discharge outlet having a substantially continuous ledge around the lower margin thereof and presenting longitudinally and transversely extending 70 ledge portions; and a sub-hopper disposed below said ledge and provided with movable sides adapted to discharge lading from the upper hopper to either side thereof, said movable sides being extended beneath the ledge and adapted when 75

in closed position to abut the longitudinally extending sections of the ledge.

4. In a car of the character described, having transversely aligned hoppers each leading to a

- 5. discharge outlet, each said outlet being reinforced around its margin by a substantially horizontally disposed ledge including longitudinally and transversely extending ledge portions presenting a four-sided reinforcement around said outlet;
- 10. chutes for directing lading to each side of the discharge outlet, each said chute including a pair of transversely extending beams spaced from each other lengthwise of the car and disposed in underlying relation with respect to the transversely extending portions of the ledge, and V-arranged doors extending between the respective beams and adapted to direct lading to either side of the discharge outlet.

5. In a railway car of the character described,

- 20. having a longitudinally extending center member including a horizontal marginal flange at the lower portion thereof; a pair of vertical beams extending transversely of the car beneath the center member and spaced from each other 25 lengthwise of the car; hopper sections on each side of the center member, each section being defined in part by a portion of the center member on one side and on three sides by sloping walls terminating in vertical wall portions having substantially horizontal lower marginal flanges, said last-named flanges in combination with the center member marginal flange forming a four-sided horizontal ledge presenting transversely and longitudinally extending ledge portions; and
- 30. V-arranged doors disposed beneath the hoppers and between the vertical beams and arranged to open to an inclined position for directing the lading to the center of the car or to the sides of the car or simultaneously side and center discharge, each said door when in closed position being adapted to abut the longitudinally extending portions of the ledge.

6. In a railway car of the character described, having a longitudinally extending center mem-

- 45. ber and hopper sections on each side of said member, each said hopper section leading to a discharge outlet at substantially the level of the lower margin of the center member; a sub-hopper below said outlet including therein a pair of fixed baffle plates and V-arranged doors lying between said baffles, said baffle plates being disposed appreciably beyond the ends of the discharge outlet and the doors being correspondingly extended; ledges adapted to span the distance intermediate 50 the ends of the outlet and the baffles; door connections disposed above said ledges and extending through the ledges; means for actuating the doors through the medium of the connections, including door-operating shafts disposed beyond

the swinging edges of the doors; and means on the ledges adapted to deflect the connections from a straight-line path.

7. In a railway car the combination with a pivotally mounted door inclined upwardly from the pivotal axis thereof when said door is in closed position; of a ledge disposed above the pivotal axis of the door and forming an abutment for the swinging edge of the door when the latter is in closed position; a door-operating 10 shaft disposed beyond the swinging edge of the door; a connection from the shaft to the door; means carried by the ledge adapted to deflect the connection from a straightline path, said means including a rigid abutment of arcuate formation 15 over which the connection is adapted to slide, said connection being adapted to engage with the door at a location intermediate the pivotal and swinging edges of the door thereby presenting an appreciable distance between the door and the ledge 20 at the junction of the door and connection; and enclosing means for the connection disposed between the ledge and the door for shielding the connection from the lading when the door is in closed position.

8. In a railway car, the combination with a pivotally mounted discharge door; of a ledge above the door; a door-operating shaft disposed beyond the swinging edge of the door; a connection deflector mounted on the ledge and having a portion of arcuate formation adapted to engage with an intermediate portion of the connection and deflect said connection from a straight-line path, said deflector including a base portion resting upon the ledge and having openings in the ledge and deflector through which the connection is adapted to extend in its passage from the shaft to the door.

9. In a load discharging car including a hopper having a pivotally mounted door, said hopper at 40 each end having a downwardly sloping floor formed with a lower vertical wall section and a laterally extending flange outstanding from said vertical wall section and lying beneath the sloping floor, said sloping floor in combination with the vertical wall section and lateral flange presenting a substantially channel-shaped lower marginal reinforcement for the hopper end wall, said door being extended lengthwise to lie beneath the laterally extending flanges of the 45 hopper end walls; a door winding shaft disposed beyond the ends of said channel-shaped reinforcements; and a door-raising connection at each end of the door disposed in the said channel reinforcement and extending between the shaft 50 and the door, each said end flange being formed with an opening through which the associated connection extends.

ARGYLE CAMPBELL.
